DESIGN FOR A DRESS

Jo Wise Meyer, New York, N. Y.

Application February 3, 1938, Serial No. 74,837

Term of patent 3½ years

To all whom it may concern:

Be it known that I, Jo Wise Meyer, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

I claim:

The ornamental design for a dress, substantially as shown.

JO WISE MEYER.
